DOWNFLOW FORCED DRAFT AIR HEATER

Filed Dec. 22, 1944

UNITED STATES PATENT OFFICE

2,431,772

DOWNSPOUT FORCED DRAFT AIR HEATER

Kephart P. Russell, Shippensburg, Pa.

Application December 22, 1944, Serial No. 569,370

1 Claim. (Cl. 126—110)

1

This invention relates to air heaters, and more particularly to those of a down draft type.

It has for one of its objects to improve generally heaters of this character so as to secure high efficiency and fuel economy in operation.

An important object is to provide a practical and highly efficient, down draft, circulatory air heater operating with minimum fuel consumption to be of maximum heating benefit in a room or other space to be heated.

Other particular and important objects and advantages to be attained will appear more fully in the following detailed description of an apparatus embodying a practical adaptation of the invention.

An illustrative but non-limiting embodiment of the invention is disclosed in the accompanying drawings, in which:

Figure 1 is a view partly in side elevation and partly in vertical section of a complete assembly of apparatus in accordance with the invention;

Figure 2 is a horizontal section taken on line 2—2 of Figure 1;

Figure 3 is a detailed sectional view, and on an enlarged scale, illustrating a practical form and arrangement of fuel burner; and

Figure 4 is a fragmentary view illustrating a modified arrangement of air blower fan and associated parts.

Referring now to the drawings in detail, the numeral 5 designates the base portion of an air heating unit which is mounted on the floor 6. Mounted on the base 5 is a vertical, generally cylindrical, hollow shell 7 constituting a combined combustion and air heating chamber. This upright cylinder 7 is closed at its upper end by a conical cover or top element 7' and the combined combustion and heating chamber thus provided is closed throughout the extent thereof except for such normally closed openings which may be hereinafter described for access to the fuel burner and such other parts as may be necessary, and an outlet opening 8 for the products of combustion, which latter, as shown, may be located substantially midway between the top and bottom of the cylindrical shell 7. As illustrated in Figure 1, the outlet opening 8 for the products of combustion is connected by a transverse pipe 9 to an upright exhaust pipe 10 whose upper end portion 11 is connected communicably in any conventional manner, to a regular flue or other take-off for the products of combustion, (not shown). As shown, the lower end portion 12 of the upright exhaust or vent pipe 10 is open and terminates adjacent the floor 6. By thus terminating the open

2

lower end portion 12 of the upright vent pipe 10 close to but spaced a short distance from the floor 6, the cold air in the immediate region of the floor is drawn into the pipe 10 by the up-draft created in said pipe by the heated products of combustion from the exhaust port 8 passing through the lateral pipe 9 into said 10 and naturally traveling upward in the pipe 10.

Surrounding the inner combustion and heating chamber shell 7, in annularly spaced relation thereto, is a cylindrical outer shell 13. Within the annular space between the inner shell 7 and the outer shell 13 is provided a frusto-conical partition 14, thus providing an annular dead air space 15 adjacent the base 5 of the heater. The top portion of the outer shell 13 extends some distance above the conical top or closure member 7' of the shell 7, and this extended upper portion of the outer shell 13 is closed by an end wall 16 except for an axial opening 17 for the attachment of an air conducting pipe to be presently described more fully in detail. Placed within the upper portion of the outer shell 13 and surrounding the conical cap or cover 7' of the inner shell 25 7 in annularly spaced relation thereto is a frusto-conical partition 18, which latter, as provided and arranged, forms an annular dead air space 19. This dead air space is provided especially as an insulating medium for the top of the heater and to provide for more effective insulation the frusto-conical partition 18 is covered throughout the extent thereof with a lining of conventional insulating material 20 of any suitable character.

An air conducting pipe or conduit 21, located externally of the outer shell 13 of the heater, has its upper end portion fitted communicably in the opening 17 in the top of the outer shell 13 and concentric with the apex of the top or closure member 7' of the inner shell 7. This pipe or conduit 21, as shown, extends vertically and parallel with the outer shell 13 and its lower end is attached to a conventional blower 22 having any ordinary fan-like rotor 23. In practice, this blower 22 may be, and preferably is, located below the floor 6, as indicated in Figure 1, or the same may be located above the floor, as shown in Figure 4.

Referring now more particularly to Figures 50 1 and 2, the blower 22 is supported on the underside of the floor 6 by a metal bracket or frame 24. The intake tube 25 of the blower 22, as shown, is fitted into an opening provided therefor in the floor 6 and covered by a screen or grid 26. 55. The blower 22 may be driven by any suitable

power element, such as for example, an electric motor 27 indicated conventionally in Figure 2. Thus, by operation of the heater, the colder air in the room or space being heated and adjacent the floor 6 is drawn into the tube or duct 25 and forced upwardly through the conduit pipe 21 and thence downwardly through the outer shell 13 and about the inner heated shell 7 whence the traveling air which has thus become heated is discharged to the outside through a single or plurality of openings 28 provided in the lower portion of the outer shell 13 adjacent the conical inner partition 14. The partition 14 thus serves to deflect the heated air downwardly and radially outward through the outlet opening or openings 28 as provided. There may be any suitable number of these openings 28. In the illustration in Figure 2, there are two of these openings 28 disposed diametrically opposite each other.

Through one of the openings 28 (see Figs. 1 and 2) a pipe 29 is projected from the air conduit pipe 21 into the shell 13, thence through aligned openings in the adjacent portions of the conical partition 14 and wall of the inner shell 7. From the pipe 21 the pipe 29 extends first upwardly, as at 30, then downward angularly, as at 31, and thence horizontally, as at 32, across the lower portion of the inner shell 7 constituting the combustion chamber of the heater. The upper part of this horizontal portion 32 of the pipe 29 is provided with a multiplicity of apertures 33 extending lengthwise thereof, and the free end portion of this horizontal part of the pipe 29 is formed with a receptacle 34 to be used as a priming cup, as will be presently described in detail. By the provision and arrangement of this pipe 29 which is of comparatively restricted size with respect to the size of the conduit pipe 21, a correspondingly restricted amount of air from the pipe 21 is forced through the pipe 29 in the operation of the heater.

The perforated part of the pipe 29 constitutes a fuel burner in the operation of which a measured quantity of fuel oil is supplied to the pipe 29 along with the air coming from the conduit pipe 21.

As shown in Figure 1, a fuel oil supply tank 35 is mounted on a bracket or shelf 33 projected from the side of the outer casing 13. From the bottom of this supply tank 35 is a pipe 37 which leads into the hipped portion of the pipe 29 (see Fig. 3) with the end of the pipe discharging downwardly and forwardly toward the bottom of the inclined portion 31 of the pipe 29. This pipe 37, which is of small capacity, is provided with a regulating and metering valve 39 (see Fig. 1) to be regulated and controlled so as to feed only a measured amount of oil, such for example, as drop by drop, from the end portion 38 of the pipe onto the bottom of the portion 31 of the burner pipe 29 as shown more clearly in Figure 3. Thus, if the pipe 29 is properly heated, the drops or otherwise measured quantity of fuel oil discharged upon the portion 31 of the burner pipe 29 is flashed into vaporous form and commingles with the air coming from the conduit pipe 21, whence the mixture is ignited as it is brought to the apertures 33 in the horizontal portion 32 of the burner pipe 29. For priming purposes, at the beginning of operation of the burner, a quantity of the oil from the pipe 37 is allowed to run into the priming cup or receptacle 34 and there ignited. After the burner pipe 29 has become heated through this priming operation, the fuel oil in the pipe 29 is vaporized, as above

noted, before reaching the combustion openings 33.

The ignition of fuel oil in the priming cup or receptacle 34 may be obviously effected by a suitable electrical or other conventional sparking device (not shown), or, if desired, an opening, normally closed by an openable door, may be provided in the inner shell 7, as indicated at 40 in Figures 1 and 2, this opening being coincident with one of the openings 28 of the outer shell for convenient access.

By the foregoing, it is apparent that an exceedingly simple yet practical and highly efficient heating apparatus is provided wherein the heated air is discharged and distributed throughout the room in the region of the floor and thus by its natural tendency to rise there is effected a thorough and economical heating of the room or space with a minimum of fuel consumption.

In most installations of the apparatus of the present invention the air blower will be located below the floor 6, substantially as indicated at Figure 1. However, in some installations, where it is not convenient or practical to put the blower below the floor, the same may be located above the floor as indicated in Figure 4, or elsewhere, as may be the more convenient or desirable.

The illustrated construction and arrangement is but one practical adaptation of the invention, and the same admits of considerable modification within the spirit and scope of the invention as defined by the appended claim. The invention, therefore, is not limited to the specific construction and arrangement shown.

Having thus described the invention, what is claimed is:

A forced down draft air circulatory heater, as described, the same comprising a vertical, elongated, hollow, inner, heater shell, closed throughout the entire extent thereof except for an exhaust vent opening in the side thereof between its top and bottom, said inner shell having a conical top end closure, an outer shell surrounding said inner shell in spaced annular relation thereto, said outer shell including a top end wall and a cylindrical side wall, an outwardly and downwardly extending, annular, frusto-conical partition between said inner and outer shells above and adjacent the bottoms of said inner and outer shells, said annular partition extending entirely from the inner shell to the outer shell and providing an annular dead air space above the bottoms of said inner and outer shells, the outer shell having at least one outlet opening in the wall thereof adjacently above said annular partition between the inner and outer shells, the upper portion of the outer shell being extended above the inner shell and provided with an axial opening, an outwardly and downwardly extending, annular, frusto-conical partition in the upper portion of said outer shell, said partition surrounding the axial opening in the shell and also being spaced concentrically about the conical end portion of said inner shell, said last-named frusto-conical partition extending entirely from the top end wall to the cylindrical side wall of the outer shell and in conjunction with the adjoining side and end wall portions of the outer shell providing an annular dead air space, a fuel burner in the lower portion of said inner shell, and a conduit pipe connected to the axial opening in the upper end of the outer shell for forcing air downwardly under

pressure through the annular space between the inner and outer shells.
